UNITED STATES PATENT OFFICE

GEORGE L. ROSENBAUM, OF ATLANTA, GEORGIA

FILTER AND STORAGE UNIT

Application filed May 9, 1929. Serial No. 361,709.

This invention relates to a reconditioner or filter and storage tank unit especially adapted for cleaning the hydrocarbon agents used in the so-called dry-cleaning of clothing, other fabrics and the like, although capable of general use as a filter and storage tank.

A prime object is to provide a construction which will particularly coact with a conventional washing machine of the centrifugal type in which a hydrocarbon dry-cleaning agent is used instead of water and a detergent, to constitute a dry-cleaning plant in treating the clothes or goods of which machine the pump returns the cleaning agent to the unit for cleansing and reuse, and further to form a plant in which the dry-cleaning operations may be carried out continuously and expeditiously without resort to frequent changing of the cleaning agent.

Another important object is to provide an exceedingly compact unitary filter and storage tank to particularly coact with the aforesaid centrifugal washing machine or the equivalent, to produce a relatively small dry-cleaning plant having minimum fire-hazard and capable of inexpensive installation in relatively small mercantile establishments such as now iron and press clothes but which find it necessary, due to the very expensive present day cleaning equipment, to send the clothes or goods if to be first dry-cleaned, to a central dry-cleaning plant.

The more specific objects and advantages will become apparent and in part will be pointed out in the description following, taken in connection with the accompanying drawing illustrating an operative embodiment.

In said drawing:

Fig. 1 is a view in side elevation of the improved unit.

Fig. 2 is a central vertical sectional view through said unit, taken on the line 2—2 of Fig. 1.

Fig. 3 is a horizontal sectional view through the unit taken on the line 3—3 of Fig. 1, and

Fig. 4 is a fragmentary vertical sectional view taken through the unit at a right angle to Fig. 2.

Referring specifically to the drawing, 10

designates a tank or container of any appropriate capacity, which has a bottom wall at 11, and a top wall at 12. Legs 13 or other supporting means are attached to or provided for the container or tank 10.

In axial alignment with the tank 10 and disposed below the same and fastened thereto is a purifying chamber in the form of a cone 14. Disposed completely across the chamber 14 and extending downwardly from the wall 11 and terminating relatively close to the apex of the chamber 14 is an imperforate baffle wall 15. The chamber 14 is adapted to contain any preferred agent for cleaning a hydrocarbon as used in the dry-cleaning of clothes or other fabrics. To this end, chamber 14 may contain a solution of caustic soda to a level above the lower edge of baffle wall 15, and for instance to the level 16. The caustic soda solution may also contain charcoal.

The previously mentioned hydrocarbon agent is directed to the chamber 14 through a pipe or conduit 17 which is located within the tank 10, and preferably extends above the top 12 thereof, so that it may be connected with a centrifugal drier or extractor of a washing machine, containing the dry-cleaning agent, rather than water. The pump of such a washing machine forces the cleaning agent through the pipe 17 and since it communicates through the wall 11 with the chamber 14, such dry-cleaning agent is discharged into the latter. Said dry-cleaning agent is caused to pass downwardly through the caustic soda solution in chamber 14, across the lower end of the baffle 15 and thence upwardly through the caustic soda solution on the opposite side of the baffle, bubbling through said solution and into a pipe 18 which communicates through the wall 11 with the chamber 14.

Eccentrically disposed within the tank or container 10 is a bath cylinder 19 which rests on the wall 11 and is of a height to extend above the wall 12. Said pipe 18 is of inverted U-shape and has its outlet end communicating with the base of the cylinder 19. Thus the cleaning agent which bubbles through the caustic soda solution passes through pipe 18 and thence into the bottom of the cylinder 19.

19. The lower portion of such cylinder 19 contains a quantity of water to the level shown at 20. In order to soften the water, when desired, alum may be added thereto.

5 A perforated baffle or plate 21 is located within the cylinder 19 above the water, and the same supports a quantity of cotton waste, cotton seed hulls, or the like, as at 22.

10 As the cleaning agent passes through the water, it is washed of traces of caustic soda or charcoal, and as it passes through the baffle 21 and material 22, all traces of water or foreign matter are removed. The cylinder 19 has an overflow opening at 23 through which 15 the finally cleaned cleaning agent discharges into the space 24 of the tank or container 10, and which space serves for the storage of the dry-cleaning agent until it is re-used. Such dry-cleaning agent in the space 24 is preferably disposed at an elevation higher than the 20 point of its use and hence it is adapted to be supplied from the space 24 by gravity through a valve-controlled outlet 25 and for instance to a centrifugal type washing machine.

25 Tank 10 may be replenished with cleaning agent through a suitable filling opening, as at 26, in the wall 12. The materials for the cylinder 19 may be placed therein when a 30 closure 27, at the top thereof, is removed, such cover being detachably bolted to the cylinder as at 28. In order to drain the cylinder 19, a valve-controlled outlet 29 is provided, the same extending from the bottom of said 35 cylinder outwardly through the container 10 adjacent the base of the latter.

30 A valve controlled draining connection 30 may be provided at the apex of the chamber 14, and a filling opening and closure for such chamber 14 may be used as at 31.

40 If desired, a sight gauge 33 of conventional form, as well as other approved accessories, may be used in connection with the tank or container 10, to permit the quantity of the 45 cleaning agent in the container to be determined.

45 As a result of the construction described, an exceedingly compact arrangement of a unit affording both a filter and a storage container is afforded, which enables continuous use of the cleaning agent, a relatively small quantity thereof to be used at a time and the cleaning action to be expeditiously and relatively inexpensive. Such a construction provides a unit for coaction with a centrifugal type washing machine or the like, which will enable a dry-cleaning plant to be produced at such low cost as to permit installation thereof in mercantile establishments finding 50 present equipment and necessary solvent too expensive to do their own dry-cleaning and which causes them to send materials for dry-cleaning to a central plant. The compactness of the structure also enables the unit to 55 be used where the conservation of space is a

prime consideration, and it further provides such an apparatus as does not unduly thwart the motion of the cleaning agent through the action of the pump of the washing machine.

While I have described the operation of the 70 apparatus in connection with the dry-cleaning agent for clothing or the like, it is to be understood that no limitation to such use is to be implied since the invention may be used as a unitary filter and storage tank in various 75 relations.

I claim as my invention:

1. A unit of the character described comprising a container, a bath cylinder therein, a purifying chamber below the container 80 adapted to receive material for purification, means within the container establishing communication between said chamber and said cylinder, said cylinder above the outlet and below the top of said means communicating with the interior of the container.

2. A unit of the character described comprising a container, a bath cylinder carried thereby, a purifying chamber carried by the container and adapted to receive material 90 for purification, and means establishing communication between said chamber and said cylinder, said cylinder being in communication with the interior of the container below the top of said means and above the 95 point of connection of said means therewith.

3. A unit of the character described comprising a container, a bath cylinder carried thereby, a purifying chamber carried by the container, said chamber having a baffle therein whereby material received for purification will travel downwardly and then upwardly, and a pipe for conveying the material after said upward travel in the chamber, from the chamber to said cylinder, said cylinder being in communication with the container below the top of said pipe and above the point of connection of said pipe thereto.

4. A unit of the character described comprising a container, a purifying chamber extending from the bottom wall of the container, a purifying chamber extending from the bottom wall of the container, a baffle depending from said bottom wall and into said 115 chamber, means to lead material to be purified into said chamber, a bath cylinder carried by the container and supported on said bottom wall, and a pipe disposed in the container communicating through said bottom 120 wall with said chamber and also communicating with said cylinder adjacent the base of the latter, said cylinder having an outlet at a distance above its base whereby the material may enter the container.

5. A unit of the character described comprising a container, a conical purifying chamber depending from the bottom wall of said container, a baffle depending from said bottom wall and into the purifying cham- 130

ber, a pipe disposed in the container adapted to conduct material to be purified and into said chamber, said pipe opening through said bottom wall, a bath cylinder within the 5 container resting on said bottom wall, a U-shaped pipe in said container communicating at one end through said bottom wall with the chamber and communicating at its other end with the base of said cylinder, said 10 container at a distance above the latter communication being in communication with the interior of said container.

6. A unit of the character described comprising a container, a conical purifying chamber depending from the bottom wall of said container, a baffle depending from said bottom wall and into the purifying chamber, a pipe disposed in the container adapted to conduct material to be purified and into said chamber, said pipe opening through said bottom wall, a bath cylinder within the container resting on said bottom wall, a U-shaped pipe in said container communicating at one end through said bottom wall with the chamber 20 and communicating at its other end with the base of said cylinder, said container at a distance above the latter communication being in communication with the interior of said container, said cylinder extending above said 25 container, a closure at the top of said cylinder, and drain means for the cylinder extending therefrom and through said container.
